(57) **CLAIM**

The ornamental design for the two channel digital thermometer, as shown and described.

DESCRIPTION

FIG. 1 shows a perspective view of a front side of a two channel digital thermometer.

FIG. 2 shows a front view of the two channel digital thermometer.

FIG. 3 shows a back view of the two channel digital thermometer.

FIG. 4 shows a first side view of the two channel digital thermometer.

FIG. 5 shows a second side view of the two channel digital thermometer.

FIG. 6 shows a top view of the two channel digital thermometer; and,

FIG. 7 shows a bottom view of the two channel digital thermometer.

The broken line showing of environmental subject matter is included for the purpose of illustrating non-claimed subject matter and forms no part of the claimed design.
